United States Patent [19]

McKinnon et al.

[11] Des. 272,136

[45]  Jan. 10, 1984

[54] MAGNETIC TIMING PROBE

[75] Inventors: Donald C. McKinnon; Edward L. Tury, both of Cheboygan, Mich.

[73] Assignee: Fox Valley Instrument Company, Cheboygan, Mich.

[] Term: 14 Years

[21] Appl. No.: 196,344

[22] Filed: Oct. 14, 1980

[51] Int. Cl. .... D10—04

[52] U.S. Cl. D10/80

[58] Field of Search .... D10/80, 57, 60, 75, D10/78, 103, 324/72.5, 158 P, 156, 149, 378, 380, 381, 382

[56]

References Cited

U.S. PATENT DOCUMENTS

2,308,088	1/1943	Liverman	D10/69 X
2,837,713	6/1958	Schoenleber	324/391
3,580,063	5/1971	Goodnow	324/391 X

OTHER PUBLICATIONS

Hewlett-Packard J.—vol. 28, No. 8—Apr. 1977—p. 9 Miniature Oscilloscope Probes.

Primary Examiner—Nelson C. Holtje
Attorney, Agent, or Firm—Stephen J. Rudy

[57]

CLAIM

The ornamental design for a magnetic timing probe, as shown and described.

DESCRIPTION

The FIGURE is a typical plan view of a magnetic timing probe showing our new design, the broken line connecting plug being environmental and forming no part of the claimed design.

U.S. Patent

Jan. 10, 1984

Des. 272,136